SHUTTLE MECHANISM FOR PAPER CARRIAGES

Walter A. Anderson, Bridgeport, Conn., assignor to Underwood Elliott Fisher Company, New York, N. Y., a corporation of Delaware

Application December 30, 1941, Serial No. 424,973

3 Claims. (Cl. 197—66)

This invention relates to paper carriages for accounting machines and more particularly to a means for controlling the shuttle movements thereof.

Certain work performed on accounting machines requires shuttle movement of the carriage between one pair of columns of a work form during certain operations, for printing figures in those columns, and shuttle movement between another pair of columns located on a different portion of the form, for printing figures therein during other operations. It is particularly desirable to have the carriage readily adjustable for shuttling between either pair of columns at the will of the operator.

It is an object of the present invention, therefore, to provide a simple and effective means for permitting ready adjustment of the paper carriage for shuttle movement at more than one place on a work form.

With this and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings:

Figure 1 is a right side elevation showing a portion of the paper carriage embodying the selectively adjustable shuttling mechanism, the parts being shown in normal or operative position.

Figure 2 is a view similar to Figure 1 but showing the shuttle control mechanism moved to inoperative position preparatory to adjusting the carriage for shuttle movement between a selected pair of columns.

Figure 3 is a detail right side elevation of a latch for holding certain of the shuttle movement initiating elements in operative position.

Figure 4 is a rear elevation of the carriage showing the conventional carriage return mechanism and the shuttle control elements that operate therewith.

Figure 5 is an exploded perspective of the shuttle movement control bar and appurtenant parts.

Figure 6 is a detail sectional elevation taken on the line 6—6 of Figure 4 showing the means for mounting the shuttle movement control bar on the paper carriage, and

Figure 7 shows an example of the work performed together with a diagrammatic illustra-

tion of the operation and shuttle movement controlling mechanisms.

The invention is herein shown as applied to a carriage of the type disclosed in the U. S. Patents 5 Nos. 1,901,135 and 2,088,982, issued to Oscar J. Sundstrand on March 14, 1933, and August 3, 1937, respectively, and embodies a shuttle control mechanism similar to that disclosed in U. S. Patent No. 1,912,168, issued to Walter A. Anderson, on May 30, 1933.

Referring to Figure 1, the carriage includes oppositely disposed end plates 2 between which is mounted a platen 3. The carriage is mounted for lateral movement on rollers, such as 4, that travel 15 along a bed 5 of the machine frame. The carriage is impelled toward the right (Figure 4), on its working stroke, by a coil spring 6 encased in a drum 7 fixed on the machine frame, spring 6 being connected by a tape 8 with the carriage proper.

The mechanism for returning the carriage to its initial position is identical with that disclosed in the above-mentioned Patent No. 1,901,135. This mechanism includes a rack 11 extending across 25 the rear of the carriage and fixed at its ends in brackets 12 secured to plates 2. Rack 11 is engageable by a pinion 13 carried on a frame 14 pivoted at 15 in the machine frame. Pinion 13 corresponds to pinion 26 in Patent 1,901,135 30 and is driven in a counter-clockwise direction by means similar to those disclosed in that patent. A spring 16, connected to a depending arm 17 of frame 14, tensions the frame clockwise about pivot 15, and normally tends to move the pinion 35 into mesh with the rack to initiate return (leftward, Figure 4) movement of the carriage. The pinion is normally withheld from engagement with the rack, however, by a latch lever 18 pivoted at 21, and having a shoulder 22 that engages a stud 23 fixed in frame 14. A spring 24, connected to lever 18, normally tensions the lever into effective latching position as shown in Figure 4.

Whenever a carriage return dog, such as 25, 45 strikes the upper end of lever 18, shoulder 22 is withdrawn from above stud 23 and the driven pinion 13 is permitted to engage rack 11 and initiate return movement of the carriage, against the tension of spring 6. Pinion 13 is disengaged 50 from rack 11 whenever a carriage return disengaging roller, such as 26, depresses an arm 27 of a bell crank 28 pivoted at 31 on the machine frame. The lower arm of bell crank 28 is connected by a link 32 to frame 14 so that counter-clockwise movement of the bell crank, incident to

its depression by roller 26, pulls frame 14 downwardly, and withdraws pinion 13 from engagement with rack 11, whereupon lever 18 again becomes effective to hold the pinion disengaged. Immediately upon disengagement of the pinion from the rack, spring 6 impels the carriage rightwardly on its working stroke.

The carriage is stopped in the various columns during its working stroke, and the machine conditioned to perform required operations in those columns, by a conventional control plate 33 (Figure 1). This plate is identical with plate 1010 disclosed in the previously mentioned Patent 2,088,982. The left edge of the plate is secured to a square shaft 34, the opposite ends of which are pivoted in end plates 2. The under side of the plate carries spaced control pins 35 (Figure 2) that engage corresponding machine operation control elements 36, certain of the pins engaging escapement elements for stopping the carriage in the various columnar positions.

A spring 37, connected to an arm 38 secured on one end of shaft 34, normally tensions plate 33 downwardly to the position shown in Figure 1 where the control pins 35 lie in association with control elements 36. A hand lever 41, pivoted at 42 on one of the plates 2, has a depending arm carrying a roller 43 that lies beneath an extension 44 formed on arm 38. A spring 45 normally tensions hand lever 41 clockwise about pivot 42. When the operator desires to manually shift the carriage from one column to another, manipulation of hand lever 41 counter-clockwise about pivot 42 until extension 44 stops against a pin 46, tilts plate 33 counter-clockwise against the tension of spring 37, and elevates pins 35 above the horizontal plane of elements 36 as shown in Figure 2. This movement of the plate raises the tabular control pins 35 out of engagement with their corresponding escapement elements 36, so that the carriage is free for manual adjustment to any desired column.

The mechanism for permitting rapid adjustment of the carriage for shuttle movement between a selected pair of a plurality of pairs of columns on a work form will now be described. Referring to Figures 4 and 5, the carriage return dogs 25-25' and carriage return disengaging rollers 26-26' are secured in predetermined, spaced positions on a plate 47 by screws 48, the positions corresponding to the columns on the work forms. Plate 47 is detachably secured to a rod 51 that extends across the carriage above plate 33, and is pivoted at its opposite ends in brackets 12. Any suitable means for securing the plate to the rod may be used. The preferred form herein shown comprises an opening 52 in the right end of the plate that embraces a pin 53 fixed in the rod, and a series of spaced notches 54 in one edge of the plate that embrace correspondingly spaced spring pressed plungers 55 (Figure 6) mounted on rod 51. The detachable mounting of plate 47 permits easy interchange of plates having different dog and roller set-ups for causing shuttling movement between pairs of columns having different locations on the work forms.

A spring 56 (Figure 1) connected between rod 51 and bracket 12 tensions the rod downwardly against a stop 57 secured in the right hand bracket 12 to normally hold plate 47 and the dogs and rollers in effective position with respect to lever 18 and arm 27. A latch 58 (Figure 3) pivoted on a screw 61 secured in bracket 12 and connected by a link 63 to hand lever 41, is notched

at its right end to embrace rod 51 when the parts are in normal position. This latch locks rod 51 and plate 47 against displacement incident to dogs 25-25' or rollers 26-26' engaging lever 18 or arm 27.

A lever 64 also pivoted on screw 61 is connected at one end by a pin and slot connection 65 to hand lever 41 and has its opposite end touching a pin 66 in a bracket 67 secured on shaft 51 by a screw 68. By this connection, manipulation of hand lever 41 to tilt plate 47 as above described, concurrently rocks lever 64 clockwise about screw 61 and causes the right end of lever 64 to tilt rod 51 and plate 47 upwardly, latch 58 being pulled upwardly to ineffective position at the same time.

The tilting of plate 47 raises dogs 26-26' and rollers 25-25' above lever 18 and arm 27, to an ineffective position, as shown in Figure 2. The carriage may then be shifted to a position where lever 18 and arm 27 lie between either the dog 25 and roller 26 or dog 25' and roller 26'. Upon the carriage being shifted to the desired position, lever 41 is released, and the parts restore to their normal positions shown in Figure 1 where they are ready for shuttle movement between the selected pair of columns.

Figure 7 shows one example of work that may be performed with the improved shuttling mechanism. The form illustrated is one that is used in printing monthly records of money orders issued in post office work. It is noted that dog 25 and roller 26 occupy positions on plate 47 to cause shuttling movement of the carriage between one pair of "amount" and "fee" columns designated as the A group, and that dog 25' and roller 26' occupy positions to cause shuttling of the carriage between another pair of "amount" and "fee" columns designated as the B group.

In operation, the carriage is stopped in the "amount" column of the A group by the conventional tabular stops 35 engaging their corresponding escapement elements 36. The amount is indexed upon the amount keyboard and printed in the "amount" column. Following this printing, the carriage automatically tabulates to the "fee" column of the A group. The amount of the fee is indexed on the keyboard and printed. Then, when the escapement automatically releases the carriage following the printing, dog 25 strikes lever 18, whereupon pinion 13 is released to engage rack 11 (Figure 4) and initiate return movement of the carriage. During the return movement, as soon as roller 26 depresses arm 27, pinion 13 is disengaged from rack 11, whereupon the carriage moves in the opposite direction a slight increment, until it is again stopped in the "amount" column of the A group by the tabular stops 35 again engaging the escapement elements 36. In this manner the carriage continuously shuttles between the columns of the A group for the printing of figures therein. The form is automatically advanced to the next printing line following the printing of the "fee," by a conventional platen feed such as that disclosed in the previously mentioned Patent 2,088,982.

After the printing is completed in the A group and the totals are taken in the usual manner, the platen is manually rotated to again bring the first line of the form into printing alignment, and hand-lever 41 is manipulated to adjust the carriage laterally to a position where lever 18 and arm 27 lie between dog 25' and roller 26'. The printing operations are performed in the 70 columns of the B group in the same manner as

above described in connection with the A group, the carriage now shuttling between the "amount" and "fee" columns of the B group. If it should be necessary to shift from group B to group A or vice versa, it is only necessary to manipulate hand-lever 41 and shift the carriage sufficiently to bring the proper set of dogs and rollers into proper relation with lever 18 and arm 27.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. In a machine of the class described, having a travelling carriage, return mechanism therefor, means for tabulating the carriage from column to column including a control plate pivoted on the carriage, a manipulative member for tilting the control plate to ineffective position, a bar pivoted in the carriage, a plate detachably secured on the bar, a plurality of pairs of dogs and rollers on the plate adapted to cooperate selectively with the return mechanism to effect shuttle movement of the carriage between different pairs of columns located on different parts of a work form, and means operable by the manipulative member to rock the dogs and rollers out of cooperative position with the return mechanism to permit rapid and selective adjustment of the carriage for shuttle movement between one or another of said pairs of columns.

2. In a machine of the class described, having a travelling paper carriage movable in one direc-

tion on a working stroke, a rack fixed on the carriage, carriage return mechanism including a bell crank pivoted for movement toward and away from the rack, a pinion on the bell crank for movement into and out of mesh with the rack, a latch lever normally restraining the bell crank to prevent engagement of the pinion with the rack, a plate on the carriage, a series of pairs of dogs and rollers located in predetermined columnar positions on the plate, said plate being movable and normally held in a position where one of the pairs of dogs and rollers cooperate with the lever and bell crank to effect shuttle movement of the carriage between a corresponding pair of columns of a work form, a manipulative member, and means operable by the manipulative member to move the plate and the dogs and rollers out of cooperative position with the lever and bell crank to enable rapid adjustment of the carriage for shuttle movement between another pair of columns.

3. In a machine of the class described, a travelling carriage, return mechanism therefor including a lever for enabling said mechanism and a lever for disabling said mechanism, a plate on the carriage, a plurality of pairs of dogs and rollers located in different pairs of columnar positions on the plate, each pair being operable to engage the levers for effecting shuttle movement of the carriage between the corresponding pair of columns, a latch for holding the plate in effective position, a manipulative member, and means controlled by the manipulative member for releasing the latch and moving the plate to permit ready adjustment of the carriage for shuttle movement between a different pair of columns.

WALTER A. ANDERSON.
